SPONGE MOP

Charles Arthur Channell, Evanston, Ill., assignor to American-Marietta Company, O'Cedar Division, Chicago, Ill., a corporation of Illinois

Filed Nov. 9, 1956, Ser. No. 621,306

8 Claims. (Cl. 15—119)

This invention relates to a sponge mop and more particularly to a sponge mop having means for squeezing mounted thereon.

The phenomenal acceptance by the housewife of sponge mops as replacements for the old rag mops has given rise to the development of various means of wringing or squeezing the sponges without touching the wet sponge and as the mops are portable, it is, of course, desirable that the means of wringing or squeezing be attached as an integral part of the mop. Further, when the competition is as keen as it has been, necessary features of new mops are that they be inexpensive and wear resistant.

The present invention provides a new and improved sponge mop which includes all of the above desirable features. A simple inexpensive squeezing linkage is attached to the mop and is operable to squeeze the sponge by bending it over upon itself. Wear of the sponge caused by repeated bending is minimized by providing the sponge with a free portion where the bending occurs so as to eliminate sharp bends and by providing a reinforcing sheet over the top of the sponge to prevent cracking of the sponge when bent.

The principal object of this invention is to provide a new and improved sponge mop having means for squeezing mounted thereon.

Another object of this invention is to produce a sponge mop wherein the mop is squeezed by being bent over upon itself.

A further object of this invention is to provide a sponge mop wherein the mop is bent and squeezed by forcing a plate at the rear of the sponge in the direction of a plate at the front of the sponge so that the sponge is squeezed therebetween.

Still another object of this invention is to produce a sponge mop of the type described wherein the sponge can be readily removed and replaced.

Yet another object of this invention is to produce a sponge mop of the type described wherein a sheet of reinforcing material is secured across the top of the sponge to prevent wearing and tearing of the sponge during the squeezing operation.

A still further object of this invention is to produce a sponge mop of the type described wherein the operating linkage is simple, inexpensive and compact.

Still another object of this invention is to produce a sponge mop of the type described having locking means for resiliently locking the operating linkage in a non-operating out-of-the-way position.

Other objects and advantages of this invention will be apparent from the following description and drawings in which:

Figure 1 is a side elevation of a sponge mop illustrative of an embodiment of this invention;

Fig. 2 is a view similar to Fig. 1 showing the sponge being squeezed;

Fig. 3 is a vertical section view taken along line 3—3 of Fig. 1;

Fig. 4 is a top plan view of the device of Fig. 1; and

Fig. 5 is an exploded perspective view of the device of Fig. 1.

Referring now to the drawings a sponge mop 10 is

2

shown having a block of sponge material 11 with a top surface 12, a front surface 13, and a rear surface 14. A front plate 15 of metal or any other rigid material is secured to the front of the top 12 of the sponge 11 and extends laterally there across. Similarly a rear plate 16 is secured and extends laterally across the rear of the top surface 12. These plates are secured to the sponge as by glue or any other suitable means. Further, the plates are provided with upwardly extending bifurcated mounting lugs 17 and 18, respectively, to permit easy attachment and removal of the sponge and plates structure from the rest of the mop assembly.

It is apparent from the drawings that the sponge has a free portion 19 intermediate the plate 15 and the plate 16. This portion 19 permits flexing of the sponge so that it can be bent over on itself when the rear plate 16 is forced arcuately downwardly in the direction of the front plate 15 by means which will be described below. The bending is thus distributed over the free portion eliminating a sharp bend and reducing the likelihood of cracking the sponge upon repeated squeezing. To further protect the sponge against wear and tear, a reinforcing sheet 20 of heavy cloth material or any other suitable flexible non-elastic substance extends across the top 12 of the sponge and is secured to the top of the front plate 15, the flexible portion 19 and the rear plate 16 by gluing or any other means. Reinforcing sheet 20 is provided with apertures suitably located to permit mounting lugs 17 and 18 to pass therethrough. This sheet fixes the relative positions of these members reinforcing the sponge against stretching and preventing cracking of the top of the sponge when it is bent over upon itself.

A handle receiving arm 21 extends upwardly and rearwardly from the front plate 15 and is provided with a bifurcated lower end 22 which is mountable over the mounting lug 17 of the front plate 15 for rigid attachment thereto as by a nut and bolt as shown at 23. The arm 21 is maintained in a rigid fixed position with respect to the plate 15 by being mounted with its flat lower surface 24 contiguous with the top of the plate 15.

A mop handle 25 is removably attachable to the handle receiving arm 21 by being inserted into a recess 26 at the upper end of the arm and locked in place as by a screw 27.

The means for squeezing the sponge will now be described. This consists generally of an operating linkage 28 having an operating lever 29 and an intermediate leverage transmitting link 30. The operating lever 29 has one end 31 pivotally mounted within a bifurcated portion 32 which extends downwardly from the handle receiving arm 21. The other end 33 of the operating lever extends upwardly and rearwardly to serve as a handle for manual operation of the linkage 28.

The leverage transmitting link 30 is channel shaped and has one end 39 pivotally secured within the bifurcated lug 18 of the rear plate 16 as by a nut and bolt 42 and extends upwardly therefrom. The other end 35 of the link is pivotally secured within the intermediate U-shaped portion 36 of the operating lever 29 as by a rivet 37 or any other suitable means.

The coaction of the lever 29 and link 30 and their pivotal connection to the arm 21 and plate 16 provide an operating linkage which is manually operable to bend over a sponge and squeeze it thoroughly. Further the lever and link assembly provides a mechanical advantage so that a housewife can squeeze the sponge dry without physical strain. To accomplish this the outer end 33 of the lever is forced away from the mop handle 25, the movement being transmitted through the link 30 to the plate 16. The path of movement of the plate 16 is confined by the sponge 11 and the reinforcing sheet 20 so that the plate moves arcuately downwardly to a position adjacent the front plate 13 with the sponge doubled over

therebetween. Rotation of lever 29 produces simultaneous translation and rotation of wringing member 30, thereby moving it from its position shown in Fig. 1 to that shown in Fig. 2 so that member 30 pushes pivot lug 18, and thus mop plate 16, into their final wringing position.

As seen in Fig. 2 there is no sharp bend in the top 12 of the sponge because of the wide free portion 19 between the plates over which the bending is distributed. However, because of the free portion 19 and the pivotal connection of the link 30 to the lever 29 and plate 16 the bending of the sponge is not controlled sufficiently to insure the rear 14 meeting the front 13 so that every portion of the sponge is opposed by another portion against which it is squeezed. In other words, there is no hinge connection between plates 15 and 16 that provides a single axis of rotation about which the two plates will always move to bring their respective outer edges accurately together. Therefore to insure accurate bending the present invention provides a stop piece 38 secured across the intermediate U-shaped portion 36 of the operating lever 29 to engage and limit the relative movement of the link with respect to the lever so that the rear 14 will always be squeezed flush with the front 13 of the sponge. As will be seen from Fig. 2, stop piece 38 operates to determine the arc through which pivot lugs 18 swing during the final squeezing action at the end of the wringing operation. During the latter part of the wringing, stop 38 readers operating lever 29 and transmitting link 30 in effect a rigid structure so far as further clockwise movement of link 30 about rivet 37 is concerned. Stop 38 thus operates to confine the movement of lugs 18 in the plane of rotation of member 30 to a predetermined arcuate path having its center at the pivot point where end 31 of lever 29 is rotatably attached, and a radius equal to the length of the third side of the triangle of which lever 29 and link 30 form the other two sides. This arcuate path brings the outer edges of the front and rear mop plates 15 and 16 and thus front surface 13 and rear surface 14 of sponge block 11 flush in their final wringing positions, when further movement of lugs 18 is stopped by the compressed folded mop.

It is seen that in the operation of the sponge mop of this invention the operating linkage just described performs two functions. The portion of the operating lever 29 between its inner end 31 and the vicinity of pivotal connection 37 and intermediate leverage transmitting link 30 together comprise an articulated bridge means effectively connecting rear mop plate 16 with front mop plate 15. The connection with front plate 15 is through the inner end of operating lever 29, which is pivoted at a location fixed with respect to mop plate 15 through bifurcated member 32 and handle receiving arm 21.

Operating lever 29 taken as a whole functions as a wringing lever by means of which the operator of the mop applies wringing force to the two mop plates. After the operator has moved the wringing lever through a certain amount of counterclockwise rotation as seen in Fig. 2, stop means 38 carried by lever 29 maintains the two arms of the articulated bridge means in a rigid condition as long as counterclockwise wringing force continues to be applied. When the operator moves the wringing lever in a clockwise direction as seen in Fig. 2 to unfold the folded sponge block, the two arms of the articulated bridge reach a point where they begin to collapse together, and continue this relative angular movement until the operating lever has been moved into a position substantially parallel to the handle of the mop.

In order to keep the operating linkage in a compact out-of-the-way position when not squeezing the sponge, locking means are provided. This locking means includes a horizontal slot 39 in the operating lever intermediate the rivet 37 and the lower end 31 of the lever. A resilient stud 40 is secured to the handle receiving arm 21 as by being welded or soldered thereto, and extends out-

ward therefrom. The stud has a bent portion 41 shaped to accommodate and be resiliently displaced by the slot 39, so that when the lever 29 is raised the stud 40 engages the slot 39 to the extent that the bent portion 41 is within the slot. The bent portion then resiliently holds the lever 29 adjacent and parallel to the mop handle 25 until sufficient pressure is applied to resiliently displace the stud to remove the bent portion from engagement with the slot.

It is apparent from the above description and from the drawings that the present sponge mop provides a structure requiring a minimum of materials and labor to produce and is of a construction wherein the upwardly extending parts are concentrated adjacent the mop handle so that the sponge can be used in places where there is low clearance. Also, the use of the cloth reinforcing sheet 28 acts as a buffer to prevent damage to furniture or the like when the mop is in use.

Further, the sponge portion of the mop of this invention can be simply removed and replaced by another mop or by a wax applicator or any other desirable implement.

I claim as my invention:

1. A sponge mop, comprising: a block of sponge material having top, front and rear portions; a front plate secured across said top portion of said sponge adjacent said front portion; a handle receiving arm secured to said front plate and extending upwardly therefrom; a handle mountable in said handle receiving arm; a rear plate secured across the top portion of the sponge adjacent said rear portion, said front and rear plates being spaced from each other, said sponge having a flexible portion intermediate said plates, and said plates being free of any hinge connection therebetween providing a single axis of rotation for relative angular movement of said two plates; a sheet of reinforcing material secured to the plates and said flexible portion of the sponge; an operating lever having an end pivotally connected to said handle receiving arm and another end extending outwardly for manual operation; an intermediate leverage transmitting link having an end pivotally connected to the rear plate and another end pivotally connected to said operating lever intermediate the ends; and a stop piece secured to the lever engageable with the link to limit relative movement of the link with respect to the lever, movement of said lever being transmitted through said link to the rear plate, said stop piece limiting the movement of said link member so as to force the rear plate arcuately downwardly in the direction of the front plate bending the sponge upon itself and squeezing it between the plates, the arcuate path followed by the point of pivotal connection between said intermediate leverage transmitting link and said rear plate at the end of said squeezing operation having its center at the point of pivotal connection between said handle receiving portion and said operating lever, and a radius equal to the length of the third side of the triangle of which the operating lever and the intermediate leverage transmitting link form the other two sides.

2. The sponge mop of claim 1 wherein the sponge and plates are detachable from said link and handle receiving arm for easy replacement.

3. The sponge mop of claim 1 wherein locking means are provided to releasably lock the operating lever in an inoperable position.

4. The sponge mop of claim 3 wherein the locking means comprises a resilient length extending from the handle receiving arm having a bent portion thereon and a slot in the operating lever shaped to accommodate said length, the lever being locked by engagement of the bent portion in the slot in a position adjacent and substantially parallel to the handle and handle receiving arm.

5. A sponge mop, comprising: a block of sponge material having top, front and rear portions; a front plate secured across said top portion of said sponge adjacent said front portion; a handle receiving arm secured to said front plate and extending upwardly therefrom; a handle

mountable in said handle receiving arm; a rear plate secured across the top portion of the sponge adjacent said rear portion, said front and rear plates being spaced from each other, said sponge having a flexible portion intermediate said plates, and said plates being free of any hinge connection therebetween providing a single axis of rotation for relative angular movement of said two plates; an operating lever having an end pivotally connected to said handle receiving arm and another end extending outwardly for manual operation; an intermediate leverage transmitting link having an end pivotally connected to the rear plate and another end pivotally connected to said operating lever intermediate the ends; and a stop piece secured to one of said operating lever and leverage transmitting link, said stop piece being engageable with the other of said members to limit relative movement of the link with respect to the lever, movement of said lever being transmitted through said link to the rear plate, said stop piece limiting the movement of said link member so as to force the rear plate arcuately downwardly in the direction of the front plate bending the sponge upon itself and squeezing it between the plates, the arcuate path followed by the point of pivotal connection between said intermediate leverage transmitting link and said rear plate at the end of said squeezing operation having its center at the point of pivotal connection between said handle receiving portion and said operating lever, and a radius equal to the length of the third side of the triangle of which the operating lever and the intermediate leverage transmitting link form the other two sides.

6. A sponge mop, comprising: a block of sponge material having top, front and rear portions; a front mop plate secured across said top portion of said sponge adjacent said front portion; a handle receiving arm secured to said front plate and extending upwardly therefrom; a rear plate secured across the top portion of the sponge adjacent said rear portion, said front and rear plates being spaced from each other, said sponge having a flexible portion intermediate said plates, and said plates being free of any hinge connection therebetween providing a single axis of rotation for relative angular movement of said two plates; a sheet of reinforcing material secured to the plates and said flexible portion of the sponge; an operating lever having an end pivotally connected to said handle receiving arm and another end extending outwardly for manual operation; an intermediate leverage transmitting link having an end pivotally connected to the rear plate and another end pivotally connected to said operating lever intermediate the ends; and a stop piece secured to one of said operating lever and leverage transmitting link, said stop piece being engageable with the other of said members to limit relative movement of the link with respect to the lever, movement of said lever being transmitted through said link to the rear plate, said stop piece limiting the movement of said link member so as to force the rear plate arcuately downwardly in the direction of the front plate bending the sponge upon itself and squeezing it between the plates, the arcuate path followed by the point of pivotal connection between said intermediate leverage transmitting link and said rear plate at the end of said squeezing operation having its center at the point of pivotal connection between said handle receiving portion and said operating lever, and a radius equal to the length of the third side of the triangle of which the operating lever and the intermediate leverage transmitting link form the other two sides.

7. A sponge mop, comprising: a block of sponge material having top, front and rear portions; a front mop plate secured across said top portion of said sponge adjacent said front portion, said mop plate having an inner and an outer edge; a rear mop plate secured across the top portion of the sponge adjacent said rear portion, said rear mop plate having an inner and an outer edge, the inner edge of said rear mop plate being spaced

from the inner edge of said front mop plate, said sponge having a flexible portion intermediate said plates, and said plates being free of any hinge connection therebetween providing a single axis of rotation for relative angular movement of said two plates; a handle receiving socket secured to one of said mop plates and extending upwardly therefrom; a handle mountable in said handle receiving socket; bridge means comprising an articulated arrangement of two links, one of said links being rotatably connected with said socket upon one of said mop plates and the other of said links being rotatably connected with the other of said mop plates; a wringing lever carried by one of said two links for applying wringing force to said other mop plate; and stop means carried by one of said bridge means and wringing lever to limit movement of said articulated links during application of wringing force to said wringing lever to maintain said articulated bridge in a rigid condition upon angular movement of the wringing lever in one direction and thereby confine the movement of the outer edge of said other mop plate at least during the latter part of the wringing operation to a predetermined arcuate path bringing said outer edge substantially flush with the outer edge of the socket-bearing plate when the two plates have swung around and compressed said sponge block between them, while permitting the articulated bridge means to collapse upon angular movement of said wringing lever in the opposite direction.

8. A sponge mop, comprising: a block of sponge material having top, front and rear portions; a front mop plate secured across said top portion of said sponge adjacent said front portion, said mop plate having an inner and an outer edge; a rear mop plate secured across the top portion of the sponge adjacent said rear portion, said rear mop plate having an inner and an outer edge, the inner edge of said rear mop plate being spaced from the inner edge of said front mop plate, said sponge having a flexible portion intermediate said plates, and said plates being free of any hinge connection therebetween providing a single axis of rotation for relative angular movement of said two plates; a handle receiving socket secured to one of said mop plates and extending upwardly therefrom; a handle mountable in said handle receiving socket; a sheet of flexible material secured to the mop plates and said flexible portion of the sponge block; bridge means comprising an articulated arrangement of two links, one of said links being rotatably connected with said socket upon one of said mop plates and the other of said links being rotatably connected with the other of said mop plates; a wringing lever carried by one of said two links for applying wringing force to said other mop plate; and stop means carried by one of said bridge means and wringing lever to limit movement of said articulated links during application of wringing force to said wringing lever to maintain said articulated bridge in a rigid condition upon angular movement of the wringing lever in one direction and thereby confine the movement of the outer edge of said other mop plate at least during the latter part of the wringing operation to a predetermined arcuate path bringing said outer edge substantially flush with the outer edge of the socket-bearing plate when the two plates have swung around and compressed said sponge block between them, while permitting the articulated bridge means to collapse upon angular movement of said wringing lever in the opposite direction.
